(57) **CLAIM**

The ornamental design for a hair dryer holder, as shown and described.

DESCRIPTION

FIG. 1 is a perspective view of the hair dryer holder showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and

FIG. 7 is a bottom plan view thereof.

FIG. 8 is another perspective view thereof; and,

FIG. 9 is a partial enlarged view of portion 9 in FIG. 1.

The dash-dash broken lines shown in the drawings illustrate portions of the hair dryer holder that form no part of the claimed design.

The short-dash-long-dash broken lines shown in FIGS. 1 and 9 depict the bounds of the enlarged view and the bounds of the area from which the enlargement was extracted and form no part of the claimed design.
